UNITED STATES PATENT OFFICE.

EDWARD C. BOYER AND FRANK RADFORD, OF DAYTON, OHIO.

CAR-PUSHER.

SPECIFICATION forming part of Letters Patent No. 697,194, dated April 8, 1902.

Application filed December 12, 1901. Serial No. 85,694. (No model.)

To all whom it may concern:

Be it known that we, EDWARD C. BOYER and FRANK RADFORD, citizens of the United States, residing at Dayton, in the county of 5 Montgomery and State of Ohio, have invented certain new and useful Improvements in Car-Pushers; and we do hereby declare the following to be a full, clear, and exact description of the invention, such as will enable others 10 skilled in the art to which it appertains to make and use the same.

This invention relates to improvements in car-pushers, and more particularly to that 15 form of such devices in which are employed means for forcing forward a car-wheel and an automatically-operated chock for following the said wheel and preventing return thereof.

It consists in certain novel constructions, 20 combinations, and arrangements of parts, as will be hereinafter described and fully claimed.

In the accompanying drawings, Figure 1 represents a perspective view of a car-pusher embodying the features of our invention; and 25 Fig. 2 represents an inverted perspective view of the same, the operating-lever being omitted. Fig. 3 represents a longitudinal section on line 3 3 of Fig. 1, the relative position of a car-wheel and rail being shown in dotted lines.

30 In the art to which this invention relates a fulcrumed lever has been employed for forcing forward a car by contact with its wheel and a spring-pressed chock has been used for following a car-wheel for preventing the return thereof; but serious objections have arisen to the present form of such devices, among which might be mentioned the fact that no means have been employed for positively 35 guiding the chock and following the wheel, whereby said chock has been subject to lateral displacement, producing liability of breakage. The base carrying the fulcrum and its lever in the previously-employed forms of car-pushers have usually been without other 40 means than its frictional contact with the rail for preventing sliding thereof, and in order to overcome these and other disadvantages and provide a cheap, simple, and efficient device we employ, as seen in the drawings, a 45 base, as 1, formed of suitable material and provided with upwardly-extending edge flanges, as 2 2, extending longitudinally and bent in-

wardly at a right angle for forming grooves for receiving and guiding a flat plate, as 3, carrying a chock 4, which plate is designed to 55 move longitudinally within said groove and be held thereby against lateral movement.

Preferably formed integral with and extending upwardly from approximately the center of base 1 is a suitable lug, as 5, designed to 60 have pivotally secured thereto an operating-lever 6, the said lug forming the fulcrum for said lever. The lever 6 is preferably apertured, as at 7, which aperture is designed to inclose lug 5, and a pin, as 8, is passed 65 through the lever 6 and lug 5 for pivotally securing the lever in place. The lever 6 is preferably formed with a curved end, as 9, designed to contact with the periphery of a car-wheel when in operation. The lever 6 may 70 be of any desired length and is preferably bent at an obtuse angle for bringing the outer end thereof within easy reach of the operator.

The chock 4 may of course be formed of any preferred shape; but we usually employ 75 a chock provided with an upper concaved face designed to snugly fit the contour of the periphery of a car-wheel, and the under face thereof is usually made flat to rest upon the rail. The chock 4 is preferably formed with downwardly-extending lugs, as 10 10, one upon either edge thereof, the space between said lugs being equivalent to the width of a rail, so that in operation the under face of the chock will rest upon the rail and the lugs 10 80 10 will remain in contact with the edges of said rail for guiding said chock in its movement. A suitable bolt, as 11, is carried by the rear end of plate 3 and passes through lug 5 at the base thereof. The bolt 11 is preferably surrounded by a spring, as 12, which spring has one end pressing the rear end of plate 3 and the opposite end pressing the rear wall of lug 5. It will be seen that the lug 5 is positioned in the path of movement of plate 95 3, whereby when the chock 4 is moved rearwardly against the pressure of spring 12 the rear end of said plate is designed to contact with said lug and have its movement limited thereby, it of course being apparent that as 100 soon as plate 3 is freed it will move forward under pressure of spring 12.

The base 1 is formed at either edge upon its under face with a broken longitudinal

flange, as 13, the space between such flanges being the same as that between lugs 10, whereby the base 1 may rest upon the rail and have its flanges extend upon either side thereof for 5 preventing lateral displacement. Each flange 13 preferably carries a pair of spaced laterally-extending lugs, as 14 14, each of said lugs being provided with a suitable threaded aperture.

10 Extending transversely of the base 1 and having its ends fit snugly between the pairs of lugs 14 is a suitable knife 15. The ends of knife 15 are apertured to register with the apertures of lug 14 for receiving suitable bolts 15 or other securing means, as 16. The under edge of knife 15 is cut away, as at 17 17, so that said knife will conform to the transverse contours of a rail and snugly fit the same; the longitudinal rear corner of said knife forming the biting or engaging edges thereof, whereby in operation said base 1 will be positively held against sliding.

In operating the present form of car-pusher the base 1 is placed upon a rail with the 25 flanges 13 engaging either side thereof, the lugs 10 also engaging their respective sides of the rail, the chock 4 being in contact with the periphery of a car-wheel, the said base 1 having been placed as near the chock 4 as 30 the rear end of plate 3 and lug 5 will permit. The round or curved end 9 of lever 6 will then be in contact with the periphery of the car-wheel and downward movement of the outer end of said lever will cause a forward 35 movement of the wheel, the curve of the contacting end of lever 6 causing a forward throw of the wheel as distinguished from the upward lifting action caused by the common form of fulcrumed lever provided with a flat 40 contacting end. Of course as the car-wheel moves forwardly the spring 12 will cause the chock 4 to closely follow the same and prevent any return movement thereof.

It will be seen by reference to Fig. 2 that 45 the blade 15 in addition to being cut away to fit the contour of the upper edge of the rail is beveled rearwardly throughout the cut-away portion of the edge, whereby the rear longitudinal corner, as above suggested, will 50 form the biting edge of the knife.

Having thus fully described our invention, what we claim as new, and desire to secure by Letters Patent, is—

1. In a car-pusher, the combination of a 55 base adapted to rest upon a rail and provided with flanges on either side for engaging the sides of the rail, upwardly and inwardly extending flanges arranged along a portion of the upper edges of the base opposite each 60 other and forming guideways, an inclined slidable chock provided with a relatively long, rearwardly-extending plate of substantially the same width as the chock and base, said plate fitting and moving in said guideways,

a spring interposed between the rear end of 65 the plate and said base for causing the chock to follow the wheel, and a lever mounted on the base for moving forward the wheel of a car, substantially as described.

2. In a car-pusher, the combination of a 70 base provided centrally with an upwardly-extending inclined lug, an operating-lever having its head portion apertured to the rear of its nose, the lug on the base extending through 75 said apertured portion of the lever and connected to such lever by a pivot, an inclined toe having a relatively long rearwardly-extending flat plate adapted to be slidably mounted on said base, inwardly-turned flanges on the top of said base, a rearwardly-extending bolt 80 carried by said plate, a spring coiled about said bolt and interposed between the rear end of the plate and the lug, the rearward movement of the plate being thus limited.

3. A car-pusher comprising in its construction a base, recessed or notched flanges extending downwardly from the longitudinal edges thereof, a pair of lugs extending laterally from each of said flanges and spaced apart, and a knife extending transversely of 90 said base, having its edge cut away to snugly fit the contour of the upper edge of a rail, and each end of said knife being secured between one of the pairs of said laterally-extending lugs, substantially as described. 95

4. A car-pusher, comprising in its construction a base, an operating-lever carried thereby, and a transversely-arranged knife secured in the under face of said base and designed to engage a rail for preventing sliding 100 of the base, the under edge of said knife being cut away to fit the contour of the upper edge of the rail, and also being beveled rearwardly for forming a biting edge of its rear longitudinal corner, substantially as de- 105 scribed.

5. A car-pusher, comprising a base adapted to fit upon a car-rail, a fulcrumed lug extending upwardly from said base, a lever provided with an opening at a point to the rear of its 110 nose for fitting upon said lug and pivoted upon and holding the same in position, the lever being thus pivoted comparatively far from the wheel which it is to engage, a nose formed on the lever which is rounded at its 115 point on its upper side so that when the handle end of the lever is depressed, the said nose will so slip upon the surface of the wheel that it will tend to push the wheel forward on the track, instead of lifting it therefrom, 120 substantially as described.

In testimony whereof we hereunto affix our signatures in presence of two witnesses.

EDWARD C. BOYER.
FRANK RADFORD.
